ATTORNEY

UNITED STATES PATENT OFFICE

WALTER G. MYLIUS, OF WILKINSBURG, PENNSYLVANIA, ASSIGNOR TO WESTINGHOUSE ELECTRIC & MANUFACTURING COMPANY, A CORPORATION OF PENNSYLVANIA

MOUNTING CONSTRUCTION FOR METERS

Application filed June 24, 1927. Serial No. 201,175.

My invention relates to electrical measuring instruments and comprises, more particularly, a construction involving the mounting of an elongated member for supporting a plurality of intermeshing gear wheels in such manner that the member shall be substantially free from buckling or torsional strains incident to the securing means.

10 My invention resides in apparatus for mounting a register on a meter-supporting frame in such manner that the tendency of the register mounting plate to buckle is substantially obviated while preventing improper meshing of the gear wheels in the gear trains; it is further characteristic of my apparatus for this purpose that it is extremely simple and embodies the desirable function of permitting removal of the register from the front of the measuring instrument.

15 It is further characteristic of my invention that there are no loose screws or washers associated with the assembled apparatus, my novel mounting permitting substantially all pressure forces existing between the securing means and the frame to be released in a simple manner.

20 It is further characteristic of my invention that the register may be placed in position to be secured to the frame in a manner requiring substantially negligible support while the operation of clamping or securing the register to the frame is being performed.

25 It is further characteristic of my invention that an elongated register having a flexible mounting constructed in accordance therewith, may be mounted on separate movable frames. Such arrangement permits a facile assembly of the register to the frame and a delicate and accurate intermeshing of the pinions on the main driving shafts, and the gear wheels on the register, by virtue of the fact that my flexible mounting permits of an adjustment of the frame structures whereby gear wheels of the registers may be properly meshed with the driving pinions.

30 My invention resides in apparatus of the character hereinafter described and claimed,

the foregoing and further characteristics of my invention being determinable from the following description.

For an understanding of one of the forms my apparatus may take, reference is to be had to the accompanying drawings in which;

Figure 1 is a view, in elevation, of a portion of an electrical measuring instrument having a register mounted thereon in accordance with my invention.

Fig. 2 is a cross sectional view of an expandible member constructed in accordance with, and for the purpose of, my invention.

Fig. 3 is a plan view of the device shown in Fig. 2, illustrating how the expandible member engages one of the frames.

Fig. 4 is a view, in cross section, of the expandible member shown in Fig. 2 taken on the line IV—IV, and

Fig. 5 is a plan view of the device shown in Fig. 2, illustrating how the expandible member engages the other frame.

Referring to Fig. 1, 1 and 2 are electrical measuring instruments mounted on a panel-board 2'. The instruments co-operate with each other through a ball mechanism 3 to indicate, respectively, volt-ampere hours on a register 4 and kilowatt hours on a register 5. The registers 4 and 5, with their associated gear trains, are suitably mounted on an elongated member 6 that supports a portion of the ball mechanism 3 and holds the gear wheels intermeshing with the operating gears of the instruments 1 and 2 in proper cooperative spaced relationship.

The plate 6 must be in exact alinement and should be free from all stresses or torsional effects incident to its own mounting in order that the delicate and co-operating gear wheels shall be free from extraneous forces and other undesirable characteristics arising by virtue of a twisted or bent plate.

In accordance with my invention, I secure the meter plate 6 to projecting members or studs 7 and 8 that extend from the bases or frames, respectively, of the meters in such manner that the plate 6 is held in substantially fixed spaced relationship to the frame of the meters and is substantially free from

any twisting or torsional effects, i. e., the strains exerted between the supporting structure and the studs 7 and 8 to hold the mounting means in position are entirely eliminated with respect to the member 6.

In accordance with my invention, I employ a plurality of expansible members that co-operate with the plate 6 and the studs 7 and 8 in such manner that the plate 6 is secured in relatively fixed spaced relationship in any desired position.

An expansible member constructed for purposes of my invention as shown in Fig. 2, for example, consists of a member 9 of substantially drum shape having a circumferential projection 10 co-operating with an insert 11 in a suitable opening in the plate 6. The member 9 may be expanded by any convenient means, for example, by providing a tapered threaded inner portion 12 adapted to co-operate with a screw 13, which, when rotated, effects separation or spreading of portions 14 and 15 of the expansible member 9. Portions 14 and 15 are separated by a slot 16 and co-operatively engage the surface 17 between the expansible member 9 and the stud 7.

The expansible member 9 and the opening in the stud 7 for the reception of said member 9 may be of any convenient shape, but I prefer that they shall be substantially circular and fit relatively close, so that, upon the insertion of the expansible member 9 in the opening of the stud 7, the frictional engagement between said member and the sides of said opening causes the plate 6 to be temporarily held in any desired position.

While the ends of the plate 6 may be secured to the respective supporting studs 7 and 8 by single expansible members 9, in the manner described above, it is desirable to utilize an arrangement permitting movement of stud 8 with respect to the plate 6 of the supporting member by securing one end of the plate 6 by means of one expansible member for holding the plate 6 in relatively fixed spaced relationship with respect to the centre of the expansible member and then securing the other end of the plate by means of a plurality of expansible members adapted to co-operate with an opening in the stud 8 that will permit relative longitudinal motion between the stud 8 and the plate 6. Fig. 1 illustrates how the expansible members 9 co-operate with the stud 8 to permit longitudinal changes in the position of the stud 8 in order that gear 20 of the meter 2 may be properly meshed with the gear wheel 21 of the plate 6. The stud 8 is provided with slots 18 that longitudinally extend in a direction similar to the direction of the longitudinal axis of the plate 6. The expansible members 9, when expanded by turning the screws 13, engage the lateral faces of the slots 18 and secure the plate

6 in a position free from transverse or lateral twisting.

The frame 22 of the meter 2 is provided with slots 23 and 24 so that the longitudinal position of the frame 22 may be varied until the gear wheel 21 and the pinion wheel 20 are properly meshed. After these gears have been properly meshed, screws 25 are tightened, and then screws 9 are turned; these screws holding the plate 6 and the members associated therewith in relatively fixed spaced relationship with respect to each other without strain or distortion.

In mounting the plate 6 upon the studs 7 and 8, it is convenient and desirable to first insert the plate 6 in proper position, in which position it is retained by the frictional engagement of the expansible members with their corresponding openings in the studs, then tighten the single expansible member on the left end of the plate 6 and then tighten the plurality of expansible members on the other end of the plate 6 after the proper gears have been meshed. When the plate 6 is secured to the studs 7 and 8 in this manner, the intermeshing gear wheels of the registers 4 and 5 and the intermeshing gear wheels between the driving mechanisms of the instruments 1 and 2 and the driven mechanisms mounted on the plate 6 are held in perfect alinement, free from torsional forces and other undesirable meshing characteristics.

While I have shown a preferred embodiment of means for securing a register plate to a supporting frame, it will of course be obvious that the same result, as hereinbefore disclosed, may be accomplished by slightly altering the construction of the mechanical parts mentioned above; for example, the expansible member 9 may be substantially square or of rectangular cross section instead of being circular, but I desire that all such changes or modifications shall be included within the spirit of the appended claims.

I claim as my invention:

1. In combination, a main base support, a plurality of primary mechanism units independently mounted thereon, secondary mechanism cooperating with said units, a bridge unit support for said secondary mechanism extending between said mechanism units, and means providing adjusting movement of one of said units.

2. In combination, a main base support, a plurality of primary mechanism units independently mounted thereon in spaced side-by-side relation, secondary mechanism cooperating with said units, means providing adjustment for one of said units relative to said main base support, a bridge unit support for said secondary mechanism extending between said mechanism units, and means for securing said bridge unit in po-

sition irrespective of the position to which said adjustable unit is adjusted.

3. In combination, a main base support, a plurality of primary mechanism units each including an auxiliary base support mounted on said main support, means for adjusting one of said auxiliary supports relative to said main support, a secondary mechanism cooperating with said units, a bridge unit support for said secondary mechanism extending between said auxiliary base supports, and means for securing said bridge unit in position irrespective of the position to which said adjustable support is adjusted.

10 4. In combination, a main base support, a plurality of primary mechanism units mounted thereon, a secondary mechanism cooperating with said units, a bridge support for said secondary mechanism extending between said units, a plurality of means spaced along the bridge for mounting the same, and means providing relative slip between the bridge and one of said mounting means.

15 5. In combination, a base support, a plurality of meter-mechanism units mounted thereon, a secondary mechanism including elements cooperating with said units and an element operated in accordance with a resultant effect of the operation of said units, 20 a bridge support for said secondary mechanism extending between said units, and means providing relative slip between said bridge and one of said units.

25 In testimony whereof, I have hereunto
30 subscribed my name this 20th day of June,
35 1927.

WALTER G. MYLIUS.
